UNITED STATES PATENT OFFICE.

HARRISON D. McFADDIN, OF EAST ORANGE, NEW JERSEY.

DESIGN FOR A LAMP SHADE, GLOBE, OR REFLECTOR.

48,527.

Specification for Design.

Patented Feb. 8, 1916.

Application filed December 11, 1915. Serial No. 66,386. Term of patent 3½ years.

To all whom it may concern:

Be it known that I, HARRISON D. McFADDIN, a citizen of the United States, residing in East Orange, county of Essex, and State of New Jersey, have invented a new and original Design for a Lamp Shade, Globe, or Reflector, of which the following is a specification, reference being had to the accompanying drawing, forming part thereof.

Figure 1 is a plan view of a lamp shade, globe or reflector embodying the design of the present invention, and Fig. 2 is a side elevation thereof.

I claim:

The ornamental design for a lamp shade, globe or reflector as shown.

HARRISON D. McFADDIN.
